Wm P. Cugnon, David Stuart & Jacob Beesley, County
of Philadelphia - Pennsylvania -

Letters Patent (Design No. 108, dated 13th Jan^g 1847,
(assigned to Wm P. Cugnon)

The schedule referred to in these Letters Patent and num-
bering part of the same.

To whom it may concern Be it known, that we Wm P.
Cugnon, David Stuart & Jacob Beesley all of the County of Phil-
adelph in the State of Pennsylvania have invented or produced a
new & useful set of Designs, which are intended to ornament a Stove,
and do hereby declare that the following is a full and exact de-
scription of the same.

Plate A. Is intended to represent the front-plate of the stove, and
is ornamented with a raised panel of scroll & leaf work, on each
side of the opening left for the fire-pot, and is represented, at a. a. a.
around the whole front of the plate there is a new and beautiful
edging of shell work, represented at b. b. b. the two sides of the plate,
which form the rounded corners of the stove, are ornamented with
leaf work at c. c.

Plate B. Is intended to form the hearth-plate in connection
with plate C, (which is intended to cover the ash-pit, which is part
of this plate) together are beautifully ornamented with scroll &
leaf work, which also indent the edge of the plate and assist
to give gracefulness to the shape of the hearth-plate as repre-
sented at d. d. d. a short distance in front of the plate C
is an ornamented ventilator represented at e.

Plate D. Is intended to represent one of the side plates. The or-
naments on this plate are disposed on 4 panels and the edging
around the plate same as Plate A, at b. b. b. it also ornaments
the lower part of the lower oven door which is also ornamented 1.

as those below, and also ornaments an even panel (though on the other side plate of this stone it ornaments a solid panel). All three of the plates described are composed of a bouquet of flowers, and leaf work; the panel near the top right corner is composed of scroll & leaf work, and is solid as above but on the other side plate of this stone forms a door for the fireplace.

We have thus described the ornamental designs which we wish to Patent, and do hereby claim the exclusive right to the same for the stove plates, as we have said them cut and displayed them.
